UNITED STATES PATENT OFFICE.

GEORGE W. BUTLER AND JOHN R. BUTLER, OF PEN ARGYL, PENNSYLVANIA.

GAME BOARD.

Application filed October 29, 1921. Serial No. 511,334.

To all whom it may concern:

Be it known that we, GEORGE W. BUTLER, and JOHN R. BUTLER, citizens of the United States, residing at Pen Argyl, in the county 5 of Northampton and State of Pennsylvania, have invented certain new and useful Improvements in Game Boards, of which the following is a specification.

This invention relates to improvements in 10 games.

The primary object of the invention is the provision of a game apparatus simulating somewhat the appearance of a checker board and having certain well defined indicia thereon for the playing of a novel, instructive and interesting game.

A further object of the invention is the provision of a playing board of the above described character, having certain parts 20 thereof provided for selective and positive positioning of playing elements.

A further object of the invention is the provision of a game of the above described character capable of being played by one 25 or more individuals.

Other objects and advantages will be apparent during the course of the following detailed description.

In the accompanying drawings; wherein 30 similar reference characters indicate corresponding parts throughout the several views.

Figure 1 is a plan view of the game board and showing various playing elements arranged thereon.

Figure 2 is a cross sectional view taken on the line 2—2 of Figure 1 and showing the relative positioning of the playing elements with respect to the game board.

In the drawings, wherein for the purpose 40 of illustration is shown the preferred embodiment of my invention, the letter A designates a game board having a plurality of playing elements B for selective positioning thereon.

The board A may be, of course, of various 45 shapes and dimensions. In the illustration, it is of square design, comprising a base 10 and the marbleized top or playing surface 11. The board A, may be, however, constructed of paper, pasteboard, wood, metal, 50 marble, or any preferred material, suitable to the taste of the owner.

The playing surfaces 11 of the board A is 55 preferably provided with a series of parallel paths 12 extending parallel with opposite sides 13 and 14 of the board A, said

series of paths 12 being evenly spaced apart. A second series of paths 15 are provided in parallel relation in respect to each other, and parallel to the opposite sides 16 and 17 of the board A. The series of paths 12 are of course, arranged over substantially the entire surface 11 as are the paths 15. The series of paths 12 intersect with the series of paths 15 at right angles, and provided a 60 plurality of squares on the playing surface 11 of equal dimensions. It is preferred, that the paths 12 and 15 be clearly designated by lines on the surface 11 in order that no confusion may result as to the course of 65 a single path. The squares provided by intersection of the series of paths are colored in contrasting manner, or otherwise sufficiently distinguished, to provide alternate squares 19 of light appearance sufficiently to 70 distinguish them from the alternate squares 20 of darker contrasting appearance. The squares 19 and 20 are so arranged upon the playing surface 11 that while they are alternately spaced with respect to each other as to their disposition intermediate parallel 75 paths, they are so positioned as to have like squares in diagonal alignment with respect to the playing board A, as in the case in the ordinary checker board arrangement. Appropriate margins 22 may be provided 80 about the edges 13, 14, 16 and 17 of the playing board A and upon the surface 11 as is clearly shown in Figure 1.

Certain points of intersection of the 85 paths 12 with the paths 15 are provided with sockets 25 extending downwardly through the playing surface 11 and the base 10, and for the reception of the playing elements B, to be subsequently described. The 90 sockets 25 may be provided in any desired number upon the playing board A, of course, keeping within the whole number of intersections provided by intersection of all of the series of paths 12 with all of the series 95 of paths 15. However, it is preferred that the sockets 25 be provided to the number of 33, and in the symmetrical cross shape arrangement illustrated in Figure 1 of the drawings.

The playing elements B are preferably all 100 of the same shape, although some of them may be made of contrasting colors or appearances. They each include a reduced shank 26 having an enlarged finger engaging head 27 upwardly of the shank 26, to 110 provide an abrupt shoulder 28. The shank

26 of a playing element B is adapted for snug and detachable insertion in any one of the sockets 25; in this position the abrupt shoulder 28 being positioned in intimate contact with the upper playing surface 11, as clearly illustrated in Fig. 2 of the drawings.

The game is primarily adapted for playing by a single individual and in view of 10 the peculiar playing elements and the sockets provided for them in the board, the game is appropriately called "Checker Peg Solitaire."

The preferred manner of playing the game is by inserting each of the pegs or playing elements B in a socket 25, in the manner indicated in Figure 1 of the drawings, leaving one of the sockets 25 free of a peg B. In the playing of a game, it is 20 a rule, that trapping or jumping of the pegs B may be effected much in the same manner as in playing a game of checkers, although the playing elements B are confined to movement along the straight lines or paths indicated on the playing board A and as above described by numerals 12 and 15. In this preferred manner of playing, it is the object of the game to jump every playing element B that is possible, removing said jumped 30 element B from its socket and taking it out of play. The skill of a player will, of course, determine the number of pegs which will be left stranded upon the board A at the end of a game. It is of course, understood, that one playing element B may only jump an adjacent element B when there is a socket 25 open on the opposite side of the jumping element B, and in the path 12 or 15 along which the element B is moving. 40 Any single movement of an element or peg B in jumping another element B must necessarily be confined to a single path 12 or 15. Considerable skill is necessary to so arrange the trapping or jumping of the pegs B as 45 to leave only one peg remaining at the end of a game. The most difficult manner of playing this game is to leave the center socket 25 open or vacant when starting the game, as indicated in Figure 1 of the drawings, and to so trap and remove the other elements B as to have the last peg or playing element B remaining in the center socket 25 at the end of a game.

Various changes in the shape, size and 55 arrangement of parts may be made to the form of the invention herein shown and described, without departing from the spirit of the invention or the scope of the claims.

We claim:

50 1. A game, comprising a supporting member having a plurality of squares thereon, of alternative contrasting appearance arranged in rows to provide intersecting straight line paths over the playing surface 55 of said element by the marginal edges of

said squares, the points of intersection of said paths having indicia thereon, and playing elements for selective disposal on the indicia provided at the points of intersection.

2. A game, comprising a supporting member having a plurality of squares thereon of alternative contrasting appearance disposed in rows to provide intersecting straight line paths over the playing surface of said member and formed by the marginal edges of 70 said squares, the points of intersection of said paths having sockets formed in said supporting member, and playing elements for selective and detachable disposal in any of said sockets.

3. A game, comprising a supporting member having a plurality of squares thereon of alternative contrasting appearance arranged in rows to provide intersecting straight line paths on the playing surface 85 of said supporting member and formed by the marginal edges of said squares, the points of intersection of said paths having depressed sockets therein, and playing elements for detachable disposal in said sockets, each of said playing elements including an enlarged head and a shank to provide an abrupt shoulder intermediate said shank and enlarged head, said shank adapted for detachable and snug disposal in any of the 90 sockets in said supporting member and to have said abrupt shoulder resting upon the surface of said supporting member.

4. A game, comprising a playing board having a surface thereof provided with a 100 series of evenly spaced parallel paths, and a second series of evenly spaced parallel paths, said second series of paths being arranged at right angles to said first mentioned series and intersecting said first 105 mentioned series of paths to provide substantially equal squares on said playing board surface, said squares being alternately designated by contrasting appearance in checker board arrangement, the points of 110 intersection of said paths having sockets extending into said playing board, and a plurality of playing elements for detachable and selective disposal in said sockets.

5. A game comprising a playing board 115 having the playing surface thereof subdivided into alternatively contrasting squares arranged in intersecting rows, said squares being marginally spaced from each other to provide intersecting straight paths intermediate the adjacent marginal lines of the squares which are arranged in rows, the points of intersection of said paths having sockets extending into said playing board, and detachable playing elements for said 120 125 sockets.

GEORGE W. BUTLER.
JOHN R. BUTLER.
